PICTURE PROJECTION SCREEN AND
METHOD OF MAKING THE SAME

Bernard M. Bodde, Hollywood, Calif.

Application February 12, 1938, Serial No. 190,250

5 Claims. (Cl. 88—24)

The invention relates to a picture projection screen, particularly a reflecting screen, and has for an object to overcome one or more defects in apertured reflecting screens now in use, as well as to simplify the manufacture thereof.

Reflecting screens now in theatre use for sound and picture reproduction are made of a fabric which is perforated in a perforating machine. Several sections of this fabric are sewed together in order to provide a screen large enough for use in a theatre. The surface of such a screen is rather rough and it collects dust which interferes with the reflecting properties. Also the seams in the screen collect dust and appear to the audience as streaks on the screen. This necessitates resurfacing the screen perhaps twice a year.

According to my invention I provide a screen suitable for theatre use which has no seams, and with better reflecting qualities than the usual fabric screen. In the course of making my screen I avoid the necessity for running the screen through a perforation machine, while nevertheless I arrive at a finished product which has an array of sound wave apertures similar to the apertures provided by the usual perforation process. I accomplish this by providing a matrix having the desired array of apertures and by spraying on it multiple coats of screen material whereby the apertures are made in the screen during the course of its formation. The one perforated matrix will of course enable the manufacture of as many apertured screens as desired.

Preferably I first form a transparent body portion by spraying multiple coats of a clear solution of cellulose ester on the perforated matrix. After this sprayed material has dried and the body portion stripped from the matrix, I then spray on the apertured body portion a thin coating of cellulose solution containing white opaque material such as titanium oxide. This forms a white reflecting surface having better reflecting properties than screens now commonly in use. Due perhaps to surface tension, the material sprayed on the apertured matrix does not fill the apertures therein, nor does the reflecting material sprayed on the apertured body portion fill the apertures therein, with the result that the finished screen has substantially the same array of apertures as the matrix.

As the matrix may be made as large as desired, a correspondingly large, seamless screen may be made thereon.

While the resulting screen is flexible, it is hard and durable and may be washed as often as de-

sired without in any way impairing the reflective qualities.

For further details of the invention reference may be made to the drawing wherein:

5 Fig. 1 is a cross section of a matrix and a screen body portion which has been sprayed thereon and about to be stripped therefrom.

Fig. 2 is a sectional view of a magnified portion of the body screen with a reflecting surface 10 thereon.

Fig. 3 is a plan view of a fragment of the apertured screen according to my invention.

Fig. 4 is a schematic view illustrating in elevation a horizontal matrix which may be employed to make the screen of my invention.

Fig. 5 is a sectional view of a portion of the matrix and screen wherein the apertures in the matrix, and the projections on the screen are tapered.

20 Referring in detail to the drawings, the matrix 1 in Figs. 1 and 4 is provided with an array of apertures 2 to permit the transmission of sound waves through a similarly apertured screen. These sound waves emanate from a loud speaker 25 to be positioned behind the screen. These screen apertures may extend throughout the area of the mouth opening of the loud speaker and the size and number thereof may be varied as desired. For example, the apertures may be smaller and 30 farther apart at the edges than they are at the center to overcome the hot spot in the projection of pictures on the screen and also I may overcome the hot spot as later described. As is usually the case, the sum of the areas of the 35 apertures may equal about five per cent of the area of the screen embracing the apertures.

The matrix 1 is composed of material which is not compatible with the screen material to be sprayed thereon. The matrix 1, for example, 40 may be made of fabric 2 having a coating 10 of resin, such as amber, thereon while the screen material may comprise a solution of cellulose acetate in a volatile solvent such as acetone, with a suitable plasticizer.

45 The matrix 1 is provided with an array of sound wave apertures 11 extending through the fabric 2 and amber 10. The apertures 11 may be slightly tapered to facilitate withdrawal of the tubular projections 12 on the screen body 3. Also 50 the apertures 11 may be about one-eighth inch in diameter and slightly larger than the desired diameter of the hole 5 in the screen body 3. In any case the holes 5 are not visible to a theatrical audience as in ordinary practice today.

Multiple coats of the cellulose ester solution

are sprayed on the under side of matrix 1 and due to surface tension the sprayed material does not fill the apertures 11 in the matrix, but does coat the sides of these apertures to the depth of amber 10. Multiple coats of this material are sprayed on the matrix to build up a transparent body portion 3 having the desired thickness. Some of the sprayed material enters the apertures 11 forming cylindrical projections as shown at 12. After the body portion 3 has dried, it is stripped from the matrix and found to have cylindrical projections 12 with apertures 5 corresponding to the matrix apertures 11.

The body portion 3, after being stripped from the matrix 1, is then suitably supported either in a horizontal or a vertical position and I spray thereon several coats of the above mentioned cellulose acetate solution to which has been added enough titanium oxide or other white or suitable opaque material to form an opaque reflecting surface 4. This surface 4 is thereby apertured as shown at 6, where the body 3 is apertured, a portion of the finished apertured screen being illustrated at 7 Fig. 3.

If desired, the opaque reflecting material which is uniformly incorporated in the solution can be sprayed directly on the matrix 1 to form an apertured reflecting screen. However, I prefer to first form the body portion 3 and then spray the reflecting surface 4 on it and on projections 12 as above described.

The above mentioned tapered feature is shown in Fig. 5 wherein the matrix 1' comprises a fabric 2' having a coating 10'. The apertures 11' in the matrix 1' are tapered outwardly as shown with the result that the projections 12' on the body portion 3' are correspondingly tapered, thereby facilitating the removal of the body portion 3' and the projections 12' from the apertured matrix 1'. The projections 12' have apertures 5', as the surface tension of the screen material which is sprayed on the underside of matrix 1', to form the body portion 3' with its integral hollow projections 12', prevents the sprayed material from filling the apertures 11' as noted above.

Preferably the reflecting surface 4 is sprayed on that side of the body portion 3 which has projections 12 and which lies adjacent the matrix 1 as that surface will be flat between the projections 12 and will have no orange peel. I find that by adding the reflecting surface 4 to that side of screen 3 on which the projections 12 lie, that a picture having greater depth, and a clearer picture from a position at the side of the theater are obtained.

The other method I have for overcoming the hot spot in picture projection is to graduate the reflecting properties of the screen so that it gives a better reflection at the edges than it does at the center. In this case the apertures 5 may all be of the same size and uniformly spaced.

For this purpose I spray the edge of the reflecting surface 4 with cellulose ester solution having titanium oxide. To this solution I add a varying amount of gray or black coloring matter for use in spraying the remainder of the reflecting surface 4 so that the reflection decreases from the edges to the center. In this way I can provide a screen the center of which has as good reflection as at present and the edges of which

have a better reflection than is possible with screens in common use, with hot spot reduction or elimination.

The feature of making a picture projection screen by spraying on the under side of the matrix is covered in my copending application S. N. 51,129 filed November 22, 1935 for "Manufacture of translucent screens."

It will be understood that the material employed for spraying the reflecting surface 4 is of the same general nature as and bonds itself to the body portion 3. Also the amount of opaque material used in the spraying solution for the surface 4, and the number of coats sprayed to form surface 4 are such that the resulting surface 4 is entirely opaque and is also a reflecting surface.

It will be apparent that various modifications may be made in the size, shape and arrangement of the apertures 5 and/or projections 12.

I claim:

1. The steps in the process of making a picture projection screen having an array of apertures therein for the transmission of sound waves which comprises spraying a solution of a transparent plastic in a volatile solvent on a matrix having said array of apertures in a body portion thereby coating said body portion and the surface surrounding said matrix apertures to form a screen body portion having integral therewith a tube in each of said apertures, allowing the sprayed material to set and stripping from said matrix the apertured sheet thus produced.

2. The steps in the process of making a picture projection screen having an array of apertures therein for the transmission of sound waves, which comprises providing in the body portion of a matrix an array of tapered apertures having a total area which is a small percentage of the total area of the screen whereby sound waves are adapted to be transmitted through the screen while projecting pictures on said screen, spraying multiple coats of a solution of cellulose ester on said matrix and lining said matrix apertures to form a screen body portion having integral therewith a tube in each of said apertures, and stripping from said matrix the apertured screen body portion thus produced.

3. The method of making a picture projection screen which comprises arranging an array of tapered apertures in a matrix of resinous material, said apertures being the same in spacing and slightly larger in size as required for sound wave transmission from a loud speaker behind a screen, spraying on said matrix a solution of screen material non-compatible with said resinous material, said solution comprising a transparent plastic dissolved in a volatile solvent, and stripping the apertured screen thus produced from said matrix.

4. The method according to claim 3 which comprises applying a reflective coating to that side of said screen having projections formed in said matrix apertures.

5. A flexible opaque picture projection screen of plastic material having an array of sound wave apertures therein of substantially the same diameter, said screen having a plurality of reflective coats successively increasing in reflectivity from the center to the edges of said screen.

BERNARD M. BODDE.
